12 Claims. (Cl. 8—43)

1
The present invention is based on the observation that materials, which, owing to their nitrogen content are capable of being dyed with acid dyestuffs, are advantageously dyed with a cobalt or chromium compound in which each atom of cobalt or chromium is bound in complex union to one molecule of each of two different ortho:ortho'-dihydroxy-monoazo-dyestuffs or to one molecule of an ortho:ortho'-dihydroxy-monoazo-dyestuff and one molecule of an ortho-hydroxy-ortho'-aminoazo-dyestuff, one of which dyestuffs is free from groups imparting solubility and the other of which contains as the sole group imparting solubility a sulfonic acid amide group, and by using an acid dyebath having a pH value which is at least sufficiently high to ensure that no demetallization occurs at the dye temperature used.

As examples of materials which owing to their nitrogen content are capable of being dyed with acid dyestuffs and are therefore suitable for being dyed by the present process, there may be mentioned leather, silk, synthetic fibers of superpolyamides (nylon) or superpolyurethanes, and above all wool.

The dyestuffs used in the present process are complex metal compounds which contain one atom of cobalt or chromium bound in complex union to one molecule of each of two different ortho:ortho'-dihydroxy-monoazo-dyestuffs or to one molecule of an ortho:ortho'-dihydroxy-monoazo-dyestuff and one molecule of an ortho-hydroxy-ortho'-aminoazo-dyestuff. As the metal forming the complex chromium is preferred.

The metalliferous dyestuffs used in the present invention therefore correspond to the composition

2
in which Me represents cobalt or chromium, F₁ represents an ortho:ortho'-dihydroxy-monoazo-dyestuff and F₂ represents an ortho:ortho'-dihydroxy-monoazo-dyestuff different from F₁ or an ortho-hydroxy-ortho'-aminoazo-dyestuff, and in which the dotted lines represent complex bonds. One of the two monoazo-dyestuffs F₁ and F₂ bound together in complex union by the same cobalt or chromium atom contains no groups imparting solubility and the other contains as the sole group imparting solubility a sulfonic acid amide group, which may contain substituents at the nitrogen atom, for example, a lower alkyl radical such as methyl, ethyl or hydroxyethyl. Hydroxyl groups are not to be considered as groups imparting solubility.

A large number of ortho:ortho'-dihydroxy-monoazo-dyestuffs of the foregoing constitution are known. The dyestuff can be made by methods in themselves known by coupling an ortho-hydroxy-diazo-compound, advantageously one of the benzene series, with a compound capable of coupling in a position vicinal to an aromatically bound hydroxyl group or enolizable or enolized keto group.

The complex metal compounds in the present process can be prepared, for example, by reacting in approximately the molecular ratio 1:1:1 an agent yielding cobalt or chromium with two ortho:ortho'-dihydroxy-monoazo-dyestuffs, of which one contains no groups imparting solubility and the other of which contains as the sole group imparting solubility a sulfonic acid amide group. The treatment with the agent yielding metal is advantageously conducted in a weakly acid to alkaline medium. Accordingly, there come into consideration as agents yielding metal more especially those metal compounds which are stable in alkaline media, for example, metal, and especially chromium, compounds of aliphatic

hydroxycarboxylic acids or advantageously aromatic ortho-hydroxy-carboxylic acids, which contain the metal in complex union. As examples of aliphatic hydroxycarboxylic acids there may be mentioned among others, lactic acid, glycollic acid, citric acid and especially tartaric acid, and as aromatic ortho-hydroxycarboxylic acids there may be mentioned, for example, those of the benzene series such as 4-, 5- or 6-methyl-1-hydroxybenzene-2-carboxylic acid and above all 1-hydroxybenzene-2-carboxylic acid, which is free from further substituents.

The complex metal compounds used in the present process can also be prepared by reacting a metal compound, especially a chromium compound, of an ortho:ortho'-dihydroxymonoazo-dyestuff containing one atom of metal compound in complex union per molecule of dyestuff (1:1-complex) with a metal-free ortho:ortho'-dihydroxymonoazo-dyestuff, and so choosing the starting materials that one of them is free from groups imparting solubility and the other contains as the sole group imparting solubility a sulfonic acid amide group. In general it is of advantage to have the sulfonic acid amide group present in the metalliferous dyestuff. The 1:1-complex, which is used as starting material, can itself be prepared by methods in themselves known, for example, by reacting the metal-free monoazo-dyestuff advantageously in an acid medium with an excess of an agent yielding metal at the boiling temperature or if desired at a temperature exceeding 100° C. The reaction of the 1:1-metal complex with the metal-free dyestuff is advantageously conducted in an aqueous neutral to alkaline medium at ordinary or a raised temperature.

The above statements with regard to ortho:ortho'-dihydroxy-monoazo-dyestuffs and their metal complexes apply also to ortho-hydroxy-ortho'-amino-monoazo-dyestuffs and complex metal compounds which contain one atom of cobalt or chromium bound to one molecule of an ortho:ortho'-dihydroxy-monoazo-dyestuff and one molecule of an ortho-hydroxy-ortho'-aminoazo-dye-

stuff. The dyeing process of this invention is conducted in a weakly acid dyebath (pH value not higher than 6.5), but the pH value must be at least sufficiently high to ensure that no decomposition of the complex occurs at the dyeing temperature, that is to say, at a raised temperature which is generally the boiling temperature of the dyebath or is only slightly lower than the boiling temperature. Such decomposition can generally be avoided when the pH value of the dyebath is higher than 3.0. It is of advantage to conduct the dyeing in an acetic acid bath.

In dyebaths which fulfill the above conditions the complex metal compounds used in the present invention exhibit a very good absorptive capacity with respect to the above-mentioned nitrogenous materials. Furthermore, they are surprisingly soluble in these baths or are taken up therein in an extremely finely divided form. The dyeings obtained by the present process, especially dyeings on wool, are distinguished by their uniformity, good properties of wet fastness and very good fastness to light.

The following examples illustrate the invention, the parts and percentages being by weight.

Example 1

3 parts of the chromium compound which con-

tains in complex union one molecular proportion of each of the two dyestuffs of the formulae

and

bound to one atomic proportion of chromium, are dissolved in 4000 parts of water, 10 parts of crystalline sodium sulfate are added, and 100 parts of well wetted wool are entered at 40-50° C. into the resulting dyebath. 2 parts of acetic acid of 40 per cent strength are then added, the bath is raised to the boil in the course of 30 minutes and dyeing is carried on for 45 minutes at the boil. Finally the wool is rinsed with cold water and dried. There is obtained blackish navy blue dyeing of good fastness to washing and light.

The complex chromium compound used in this example may be prepared as follows:

3.65 parts of the sodium salt of the dyestuff from diazotized 2-amino-1-hydroxybenzene-4-sulfonic acid amide and 2-hydroxynaphthalene and 3.31 parts of the sodium salt of the dyestuff from diazotized 5-nitro-2-amino-1-hydroxybenzene and 2-hydroxynaphthalene, both dyestuffs being in the form of a moist paste (filter cake), are stirred in 300 parts of water and mixed with 25 parts of a solution of sodium-potassium chromosalicylate having a chromium content of 2.6 per cent.

After the addition of 6 parts of sulfonated castor oil the whole is heated to the boil and maintained at that temperature under reflux for 3 hours. At the end of this period the whole is allowed to cool, and the dyestuff is precipitated by the addition of sodium chloride. After being filtered off and dried, the dyestuff is a black water-soluble powder.

The dark green solution of sodium-potassium chromosalicylate is obtained by boiling 362 parts of an aqueous chromic sulfate solution having a chromium content of 7.2 per cent, with 138 parts of salicylic acid, dissolving the resulting chromosalicylic acid by the addition of 166 parts of sodium hydroxide solution of 30 per cent strength and a sufficient quantity of potassium hydroxide solution of 37 per cent strength to render the medium alkaline to phenolphthalein, and making up the mixture to 1000 parts with water.

In the following table are given a few further complex metal compounds with which valuable dyeings on wool fast to washing and light can also be obtained in the manner described above. In column I is given the complex-forming metal, in columns II and III the two ortho:ortho'-dihydroxymonoazo-dyestuffs or the ortho:ortho'-dihydroxymonoazo-dyestuff and the ortho-hydroxy-ortho'-aminoazo-dyestuff bound to the

metal, and in column IV the tints obtainable on wool with the various complex metal compounds:

No.	I	II	III	IV
1.....	Cr	Diazotized 2-amino-1-hydroxybenzene-4-sulfonic acid amide → 1-phenyl-3-methyl-5-pyrazolone.	Diazotized 5-nitro-2-amino-1-hydroxybenzene → 2-hydroxynaphthalene.	brown.
2.....	Cr	do	diazotized 4-nitro-2-amino-1-hydroxybenzene → 2-hydroxynaphthalene.	Do.
3.....	Cr	diazotized 2-amino-1-hydroxybenzene-4-sulfonic acid amide → 2-hydroxynaphthalene.	diazotized 4-nitro-2-amino-1-hydroxybenzene → acetooacetic acid anilide.	violet-brown.
4.....	Cr	diazotized 4-nitro-2-amino-1-hydroxybenzene → 2-hydroxynaphthalene-6-sulfonic acid amide.	diazotized 4-nitro-2-amino-1-hydroxybenzene → 2-hydroxynaphthalene.	reddish grey.
5.....	Cr	diazotized 2-amino-1-hydroxybenzene-4-sulfonic acid amide → 1-phenyl-3-methyl-5-pyrazolone.	diazotized 4-nitro-6-acetylaminio-2-amino-1-hydroxybenzene → 2-hydroxynaphthalene.	yellow-brown.
6.....	Co	diazotized 2-amino-1-hydroxybenzene-4-sulfonic acid amide → 2-hydroxynaphthalene.	diazotized 4-chloro-2-amino-1-hydroxybenzene → 5,8-dichloro-1-hydroxynaphthalene.	bluish bordeaux.
7.....	Co	do	diazotized 4-chloro-2-amino-1-hydroxybenzene → 2-hydroxynaphthalene.	bordeaux.
8.....	Cr	diazotized 2-amino-1-hydroxybenzene-4-sulfonic acid amide → 1-phenyl-3-methyl-5-pyrazolone.	diazotized 4-chloro-5-nitro-2-amino-1-hydroxybenzene → 2-aminonaphthalene.	brown.

Example 2

100 parts of nylon yarn are introduced into a dyebath at 50° C., which contains in 4000 parts of water 2 parts of the chromiferous dyestuff obtained as described in the first paragraph of Example 1, 40 parts of crystalline sodium sulfate and 0.5 part of acetic acid of 40 per cent. strength. The temperature is raised to 95° C. in the course of 30 minutes and dyeing is carried on for one hour at that temperature. There is obtained a deep navy blue dyeing of very good fastness to washing and rubbing.

Example 3

100 parts of well neutralized chrome leather (box calf, ox hide, kid, etc.) are entered into a dyebath containing a quantity of water at 60° C. amounting to three times the weight of the leather, and there is added a dyestuff solution containing 0.5 part of the cobalt-containing dyestuff No. 6 of the table dissolved in 50 parts of water. The leather is dyed for 45 minutes, and then fat-liquored in the same or a fresh bath. The leather is dyed a bluish bordeaux tint.

What is claimed is:

1. A process for dyeing materials, which owing to their nitrogen content are capable of being dyed with acid dyestuffs, which process comprises dyeing with a member selected from the group consisting of chromium and cobalt compounds in which each atom of said metals is bound in complex union to one molecule of two different dyestuffs one of which is an ortho:ortho'-dihydroxy-monoazo-dyestuff and the other of which is selected from the group consisting of ortho:ortho'-dihydroxy-monoazo-dyestuffs and ortho-hydroxy-ortho'-amino-monoazo-dyestuffs, one of which dyestuffs is free from groups imparting solubility and the other of which contains as the sole group imparting solubility a sulfonic acid amide group, which process comprises furthermore dyeing in an acid dyebath of which the pH value is at least high enough to ensure that no demetallization occurs at the dyeing temperature.

dyed with acid dyestuffs, which process comprises dyeing with a cobalt compound in which each atom of cobalt is bound in complex union to one molecule of two different ortho:ortho'-dihydroxy-monoazo-dyestuffs, one of which is free from groups imparting solubility and the other of which contains as the sole group imparting solubility a sulfonic acid amide group, which process comprises furthermore dyeing in an acid dyebath of which the pH value is at least high enough to ensure that no demetallization occurs at the dyeing temperature.

3. A process for dyeing materials, which owing to their nitrogen content are capable of being dyed with acid dyestuffs, which process comprises dyeing with a chromium compound in which each atom of chromium is bound in complex union to one molecule of two different ortho:ortho'-dihydroxy-monoazo-dyestuffs, one of which is free from groups imparting solubility and the other of which contains as the sole group imparting solubility a sulfonic acid amide group, which process comprises furthermore dyeing in an acid dyebath of which the pH value is at least high enough to ensure that no demetallization occurs at the dyeing temperature.

4. A process for dyeing materials which owing to their nitrogen content are capable of being dyed with acid dyestuffs, which process comprises dyeing with a chromium compound in which each atom of chromium is bound in complex union to one molecule of an ortho:ortho'-dihydroxy-monoazo-dyestuff which contains as the sole group imparting solubility a sulfonic acid amide group, and to one molecule of an ortho-hydroxy-ortho'-amino-monoazo-dyestuff which is free from groups imparting solubility, which process comprises furthermore dyeing in an acid dyebath of which the pH value is at least high enough to ensure that no demetallization occurs at the dyeing temperature.

5. A process for dyeing wool which comprises dyeing with a cobalt compound in which each atom of cobalt is bound in complex union to one

2. A process for dyeing materials, which owing to their nitrogen content are capable of being

7

molecule of two different ortho:ortho'-dihydroxy-monoazo-dyestuffs, one of which is free from groups imparting solubility and the other of which contains as the sole group imparting solubility a sulfonic acid amide group, which process comprises furthermore dyeing in an acid dyebath of which the pH value is at least high enough to ensure that no demetallization occurs at the dyeing temperature.

6. A process for dyeing wool which comprises dyeing with a chromium compound in which each atom of chromium is bound in complex union to one molecule of two different ortho:ortho'-dihydroxy-monoazo-dyestuffs, one of which is free from groups imparting solubility and the other of which contains as the sole group imparting solubility a sulfonic acid amide group, which process comprises furthermore dyeing in an acid dyebath of which the pH value is at least high enough to ensure that no demetallization occurs at the dyeing temperature.

7. A process for dyeing wool which comprises dyeing with a chromium compound in which each atom of chromium is bound in complex union to one molecule of an ortho:ortho'-dihydroxy-monoazo-dyestuff which contains as the sole group imparting solubility a sulfonic acid amide group, and to one molecule of an ortho-hydroxy-ortho'-amino-monoazo-dyestuff which is free from groups imparting solubility, which process comprises furthermore dyeing in an acid dyebath of which the pH value is at least high enough to ensure that no demetallization occurs at the dyeing temperature.

8. A process which comprises dyeing wool in an acid dyebath of which the pH value is at least high enough to ensure that no demetallization occurs at the dyeing temperature with a chromium compound in which each atom of chromium is bound in complex union to one molecule of the dyestuff corresponding to the formula

and to one molecule of the dyestuff corresponding to the formula

9. A process which comprises dyeing wool in an acid dyebath of which the pH value is at least high enough to ensure that no demetallization occurs at the dyeing temperature with a chromium compound in which each atom of chromium is bound in complex union to one molecule of the dyestuff corresponding to the formula

and to one molecule of the dyestuff corresponding to the formula

8

10. A process which comprises dyeing wool in an acid dyebath of which the pH value is at least high enough to ensure that no demetallization occurs at the dyeing temperature with a chromium compound in which each atom of chromium is bound in complex union to one molecule of the dyestuff corresponding to the formula

15 and to one molecule of the dyestuff corresponding to the formula
